GARMENT HANGER

Benjamin Zuckerman, New York, N.Y., assignor to Mister Hanger, Inc., New York, N.Y., a corporation of
New York

Filed Mar. 8, 1965, Ser. No. 84,153

Term of patent 14 years

(Cl. D80—8)

FIG. 1

FIGURE 1 is a front elevation of a garment hanger, its other side having the exact same appearance,

I claim:

The ornamental design for a garment hanger, as shown and described.
